[57] **CLAIM**

The ornamental design for a skirt, substantially as shown and described.

DESCRIPTION

FIG. 1 is a front perspective view of a skirt showing my new design;

FIG. 2 is a top plan view of the skirt in unbuttoned and unfolded condition;

FIG. 3 is a bottom plan view thereof;

FIG. 4 is a plan view of the top of the skirt folded in half in unbuttoned condition;

FIG. 5 is a view similar to FIG. 4 of the side of the skirt opposite that shown in FIG. 4;

FIG. 6 is a front elevational view of the skirt folded in half and buttoned; and

FIG. 7 is a rear elevational view thereof.

FIG. 1
